UNITED STATES PATENT OFFICE.

HARRY A. DOUGLAS, OF BRONSON, MICHIGAN, ASSIGNOR TO DOUGLAS & RUDD MANUFACTURING COMPANY, OF BRONSON, MICHIGAN, A CORPORATION OF MICHIGAN.

ELECTRICAL CONNECTOR.

1,224,908.

Specification of Letters Patent.

Patented May 8, 1917.

Application filed May 11, 1915. Serial No. 27,456.

To all whom it may concern:

Be it known that I, HARRY A. DOUGLAS, citizen of the United States, residing at Bronson, in the county of Branch and State of Michigan, have invented a certain new and useful Improvement in Electrical Connectors, of which the following is a full, clear, concise, and exact description, reference being had to the accompanying drawings, forming a part of this specification.

My invention relates to circuit couplers or connectors, and has for one of its objects the provision of such a device wherein two members are made relatively movable longitudinally of the structure to bring these members in either of two alternative relations, in one of which circuit closure is effected (assuming the circuit to be intact elsewhere) and in the other of which the circuit is opened. By means of my invention supplemental means for maintaining the relative position of the members when the circuit is opened need not be provided, since the contact portions of the connector then may perform this function. This feature of my invention enables me to maintain constant engagement between contacts carried by the relatively movable members whether the circuit be opened or closed; though I do not limit myself to this characteristic.

The invention also contemplates the provision of a simplified electrical union between a binding screw or other terminal carried by a plug or other mounting of insulating material, and a switching contact carried by the plug. This feature of the invention has been embodied in an intermediate portion of an established or established circuit, but is not to be limited to its location.

The invention has other characteristics and will be more fully explained by reference to the accompanying drawing illustrating the preferred embodiment thereof, and in which Figure 1 is a view, mainly in longitudinal section, illustrating the circuit opening adjustment of the connector; Fig. 2 is a view generally similar to Fig. 1, but illustrating the circuit closing adjustment of the device; Fig. 3 is a side elevation of a part of the structure; and Figs. 4 and 5 are perspective views of component parts.

Like parts are indicated by similar char-

acters of reference throughout the different figures.

The structure includes a cylindrical metallic shell 1 provided with bayonet slots 2 at one end, there to afford means for the attachment of some circuit continuing device, which is shown as being a small incandescent lamp 3, whose filament 4 is provided with terminals 5 and 6 carried by the base of the lamp, this base being herein termed a contact carrier. Pins 7 project from the base of the lamp to constitute with the slots 2 bayonet catches for maintaining the lamp and shell together.

The shell 1 is in axial alinement with a plug of insulating material 8, that is also herein termed a contact carrier, this plug being here shown as being removably held within one end of the shell.

The plug is centrally recessed longitudinally of the shell, one end of this recess being larger than the other to afford a shoulder 9. A cylindrical current conducting contact 10 is received in the outer end of the recess, the base of this contact being provided with a flange 11 clamped against the shoulder 9 by a ring nut 9' received in the larger end of the recess and there having threaded engagement with the plug 8, the contact 10 passing through the bore of the ring nut. The outer end of the contact 10 is reduced to form a shoulder 12. A plunger of insulating material 13 projects through the outer and contracted end of the bore of the contact 10, the base of the plunger being enlarged to limit the extent of its outward movement by engaging the contiguous shoulder 12. A coiled spring 14 is inclosed within the contact 10. The ends of this spring are seated within the recesses provided in the inner ends of the plunger 13 and plug 8, the spring being under such compression as to force the plunger 13 outwardly when the ends of the shell 1 are not sufficiently occupied by circuit continuing elements. The outer end of the plunger 13 is provided with a metallic contact cap 15, the plunger 13 constituting the means by which the contact 15 is carried by the contact carrier 8.

This cap is out of engagement with the contact element 10 when the plunger is placed in its outermost position by the spring 14, as indicated in Fig. 1, but which cap or circuit closer 15 is brought

into engagement with the contact 10 when the circuit continuing elements are fully within the ends of the shell. The circuit closer 15 constitutes a current conducting contact that co-operates with the current conducting contact 10 and is adapted for separable engagement therewith, while at the same time maintaining constant engagement with the current conducting contact 5.

10 Contact 10 is pressed against terminal 17 by the ring nut 9', while the metallic shell 10' is provided with an insetting spring tongue 10² which presses upon the upper end of the terminal 16. The spring tongue 10² thus constitutes an improvement upon the pin or screw connections hitherto existing between parts corresponding to the elements 10' and 16. The shell 1 thus conveys current between the elements 10' and 6, the 15 device being thus a "single pole" connection, but to which the invention is not to be limited.

Generally it is not desirable to have facility for adjusting the lamp to in and out 20 of circuit positions while mechanically interconnected with the shell 1. I therefore arrange the plug 8 as illustrated, the plug shown carrying the screw terminals 16, 17. Means are afforded whereby this plug 8 may 25 have two distinct positions with respect to the shell while coupled therewith, and that are spaced apart longitudinally of the shell. In the outermost position of the plug 8 the spring 14 projects the plunger 13 to its 30 outermost position in which the circuit closer 15 is out of engagement with the contact 10, whereby the circuit is then opened. When the plug 8 is in its inner position, the cap 15 is forced into engagement with the 35 contact 10 to close the circuit. The outer end of the contact 10 is desirably longitudinally slotted to provide spring contact fingers for affording firm electrical connection with the cap 15. The spring 14 is never 40 in circuit, so that its resiliency is not reduced. The means which I preferably employ for adjusting the member 8 longitudinally of the structure resides in a pair of bayonet pins or projections 18, carried by 45 said member, and a pair of bayonet slots 19 in the lower end of shell 1, and so formed as to provide an inner pair of seats 20 and an outer pair of seats 21, the two pairs of 50 seats thus being spaced apart longitudinally 55 of the shell. When the projections 18 are received by the inner seats 20 the circuit is closed, and when received by the outer seats 21, the circuit is opened. The angular displacement of one pair of seats from the 60 other may be disregarded, slight angular displacement being desired only to permit of the ready transfer of the pins 18 from one pair of seats to the other. This advantage is secured, since the contact 5 may 65 remain in engagement with the contact 15

irrespective of the position of the plug 8 to hold the parts in assembly.

To insure the retention of the projections 18 in the bayonet seats, said seats are provided with horns 20', 21'.

To insure the maintenance of the mechanical union between the shell 1 and the lamp 3 when the plug 8 is removed, said shell carries strip springs 22 that are desirably integrally formed with the shell, 75 and which press the bayonet pins 7 upwardly against their seats and longitudinally of the shell 1. That is, the springs 22 are disposed transversely of the shell, and may be flexed longitudinally thereof, each 80 of the springs being connected at one end with the shell and at the other end being free to exert pressure upon the pins 7.

While I have herein shown and particularly described the preferred embodiment of 85 my invention, I do not wish to be limited thereto, as changes may readily be made without departing from the spirit of the invention.

Having thus described my invention, I 90 claim as new and desire to secure by Letters Patent the following:

1. A circuit connector including a contact carrier; a circuit terminal carried by and entering the carrier; a contact carried 95 upon the exterior of the carrier; and an insetting spring connected with the contact and pressing upon the circuit terminal.

2. A circuit connector including a contact carrier; a circuit terminal carried by and 100 entering the carrier; a contact carried upon the exterior of the carrier; and an insetting spring integrally formed with the contact and pressing upon the circuit terminal.

3. A circuit connector including a contact 105 carrier; two current conducting contacts carried thereby; means for breaking engagement between said contacts; a second contact carrier; a third current conducting contact which is carried by the second contact carrier; and means whereby the contact carriers may be relatively positioned to enable the third current conducting contact to engage one of the first aforesaid contacts and force it into engagement with the other 110 115 of the first aforesaid contacts.

4. A circuit connector including a contact carrier; two current conducting contacts carried thereby; means for breaking engagement between said contacts; a second 120 contact carrier; a third current conducting contact which is carried by the second contact carrier; and a shell for holding said contact carriers and enabling the contact carriers to be so relatively positioned as to 125 cause the third current conducting contact to engage one of the first aforesaid contacts and force it into engagement with the other of the first aforesaid contacts.

5. A circuit connector including a contact 130

- carrier; two current conducting contacts carried thereby; a spring for effecting separation of said contacts; a second contact carrier; a third current conducting contact which is carried by the second contact carrier; and means whereby the contact carriers may be relatively positioned to enable the third current conducting contact to engage one of the first aforesaid contacts and force it into engagement with the other of the first aforesaid contacts against the force of said spring, said latter means also enabling the contact carriers to be held farther apart by the spring to permit the spring to separate the contacts carried by the first carrier.
6. A circuit connector including a contact carrier; two current conducting contacts carried thereby; a spring for effecting separation of said contacts; a second contact carrier; a third current conducting contact which is carried by the second contact carrier; and a shell for holding said contact carriers and enabling the contact carriers to be so relatively positioned as to cause the third current conducting contact to engage one of the first aforesaid contacts and force it into engagement with the other of the first aforesaid contacts against the force of said spring, said shell being constructed to coöperate with the spring also to hold the carriers farther apart and to permit the spring to separate the contacts carried by the first carrier. 30
10. A circuit connector including a shell having a bayonet slot; a contact carrier provided with a projection for reception within the seat afforded by said slot; and a strip spring carried by the shell and disposed transversely thereof, this spring pressing upon the projection longitudinally of the shell to hold the projection in said seat. 35
15. A circuit connector including a contact carrier; two current conducting contacts carried thereby; a spring for effecting separation of said contacts; a second contact carrier; a third current conducting contact which is carried by the second contact carrier; and a shell for holding said contact carriers and enabling the contact carriers to be so relatively positioned as to cause the third current conducting contact to engage one of the first aforesaid contacts and force it into engagement with the other of the first aforesaid contacts against the force of said spring, said shell being constructed to coöperate with the spring also to hold the carriers farther apart and to permit the spring to separate the contacts carried by the first carrier. 40
20. A circuit connector including a contact carrier; two current conducting contacts carried thereby; a spring for effecting separation of said contacts; a second contact carrier; a third current conducting contact which is carried by the second contact carrier; and a shell for holding said contact carriers and enabling the contact carriers to be so relatively positioned as to cause the third current conducting contact to engage one of the first aforesaid contacts and force it into engagement with the other of the first aforesaid contacts against the force of said spring, said shell being constructed to coöperate with the spring also to hold the carriers farther apart and to permit the spring to separate the contacts carried by the first carrier. 45
25. A circuit connector including a contact carrier; two current conducting contacts carried thereby; a spring for effecting separation of said contacts; a second contact carrier; a third current conducting contact which is carried by the second contact carrier; and a shell for holding said contact carriers and enabling the contact carriers to be so relatively positioned as to cause the third current conducting contact to engage one of the first aforesaid contacts and force it into engagement with the other of the first aforesaid contacts against the force of said spring, said shell being constructed to coöperate with the spring also to hold the carriers farther apart and to permit the spring to separate the contacts carried by the first carrier. 50

In witness whereof, I hereunto subscribe my name this 8th day of August A. D., 1914.

HARRY A. DOUGLAS.
